(57) **CLAIM**

The ornamental design for tripod camera mount [J] as shown and described.

DESCRIPTION

FIG. 1 is a front, top, and right perspective view of a tripod camera mount;
FIG. 2 is a rear, bottom, and left perspective view thereof;
FIG. 3 is a front view thereof;

FIG. 4 is a rear view thereof;
FIG. 5 is a left view thereof;
FIG. 6 is a right view thereof;

FIG. 7 is a top view thereof; and,
FIG. 8 is a bottom view thereof.

FIG. 9 is a front, top and right perspective view of an alternate embodiment of the tripod camera mount;
FIG. 10 is a rear, bottom, and left perspective view thereof;

FIG. 11 is a front view thereof;
FIG. 12 is a rear view thereof;

FIG. 13 is a right view thereof;
FIG. 14 is a left view thereof;
FIG. 15 is a top view thereof;
FIG. 16 is a bottom view thereof.

FIG. 17 is a front, top and right perspective view of the alternate embodiment of the tripod camera mount;
FIG. 18 is a rear, bottom, and left perspective view thereof;

FIG. 19 is a front view thereof;
FIG. 20 is a rear view thereof;

FIG. 21 is a right view thereof;
FIG. 22 is a left view thereof;
FIG. 23 is a top view thereof;

(Continued)

{NEW}

FIG. 24 is a bottom view thereof.

FIG. 25 is a front, top and right perspective view of the alternate embodiment of the tripod camera mount, wherein the components are shown in an expanded position;

FIG. 26 is a bottom, rear, and right view thereof;

FIG. 27 is rear view thereof;

FIG. 28 is a front view thereof;

FIG. 29 is a right view thereof;

FIG. 30 is a left view thereof;

FIG. 31 is atop view thereof; and,

FIG. 32 is a bottom view thereof.

The ornamental design which is claimed is shown in solid lines in the drawings. The broken lines in the drawings form no part of the claimed design. Broken lines formed by equal length dashes (i.e., dash-dash) show unclaimed subject matter. Broken lines form by unequal length dashes (i.e., dash-dot) define bounds of the claimed design.

1 Claim, 29 Drawing Sheets
